DICE AGITATING AMUSEMENT DEVICE

William E. Worth, Kodiak, Territory of Alaska

Application May 10, 1956, Serial No. 584,002

3 Claims. (Cl. 273—145)

This invention generally relates to an amusement device and more particularly a device for providing entertainment for all ages which includes a receptacle for shaking dice together with means for positioning the dice for easy viewing thereof.

An object of the present invention is to provide an amusement device in the form of an enclosed receptacle having a plurality of dice therein with certain indicia on each face of each dice wherein novel means is provided for orientating the device in alignment for easy viewing after the dice have been thoroughly agitated.

Another object of the invention is to provide an amusement device wherein the plurality of dice may be provided with indicia wherein a novel game may be employed in conjunction with the amusement device.

Other objects of the present invention will reside in its simplicity of construction, entertaining and its relative inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the amusement device of the present invention;

Figure 2 is a vertical sectional view taken substantially upon a plane passing along section line 2—2 of Figure 1 illustrating the construction of the device;

Figure 3 is a plan sectional view taken substantially upon a plane passing along section line 3—3 of Figure 2 illustrating further structural details of the amusement device;

Figure 4 is a perspective view of the amusement device with the dice disposed in their reading position with the closure member pivoted to an open position;

Figure 5 is a sectional view taken substantially upon a plane passing along section line 5—5 of Figure 4 illustrating further structural details of the amusement device; and

Figure 6 is a perspective view of one of the dice employed with the present invention.

Referring now specifically to the drawings, the numeral 10 generally designates the amusement device of the present invention including a receptacle generally designated by the numeral 12 which includes a top wall 14, a front wall 16, a rear wall 18, side walls 20 and inwardly extending ledges 22 on the rear wall 18 and the side walls 20. The juncture between the top wall 14 and the front wall 16, rear wall 18 and side walls 20 is rounded for providing a smooth contour and the entire receptacle 12 may be constructed of plastic material or similar type of material which may be transparent or opaque.

The front wall 16 is provided with an enlarged opening 24 extending substantially throughout the bottom area of the front wall 16 and the side walls 20 are provided with tabs or lugs 26 extending outwardly therefrom in

2

planar relation for pivotally mounting a closure member 28 on a pivot pin 30 extending through the lugs 26. The closure member 28 is integrally formed with a platform or shelf 32 which is in perpendicular relation to the closure member 28 wherein the platform or shelf 32 forms a bottom for the receptacle 12 when the closure member 28 is in closed position substantially as is illustrated in Figure 2. The outer free edge of the closure member 28 is provided with a pair of outwardly extending tabs 34 forming handles for manipulating the closure member 28 and limiting the inward movement thereof. Also, an inwardly extending member 36 is formed on the free edge of the closure 28 and a pair of generally L-shaped side members 38 is provided on the closure member 28 and shelf 32 with one end of the side members 38 connected to the inwardly extending edge 36 and the other end of the edge terminating in spaced relation to the free edge of the shelf 32. Interconnecting the shelf 32 and the closure member 28 is a curved ramp 44 for guiding the plurality of dice 42 downwardly into contact with the inwardly extending edge 36 for aligning the dice 42 for reading or viewing the same.

It will be noted that the shelf 32 is longer than the closure member 28 and is longer than the height of the opening 24 wherein the outer free edge thereof will form a stop or limit means for limiting the downward pivotal movement of the closure member 28 towards its open position substantially as illustrated in Figure 5 thereby assuring that the closure member 28 will be disposed in substantially perpendicular relation. Also, the side members 38 are each provided with a concave upper edge 46 having substantially the same curvature as the ramp 44 so that the dice 42 may be more easily observed by the operator of the device.

Each of the side walls 20 is provided with a detent 48 adjacent the lower edge thereof for reception in recesses 50 in the side members 38 adjacent the inner end thereof for retaining the closure member 28 in its vertical closed position in relation to the opening 24 whereby the receptacle 12 may be utilized as an agitator for shaking the dice 42. After the dice 42 have been well shaken, the receptacle 12 may be placed on a supporting horizontal surface or held in the hand with the top 14 being disposed upwardly. The force of gravity will assure that all of the dice 42 come to rest upon the shelf 32 which forms a closure for the lower end of the receptacle 12. The tabs 34 may then be grasped and the closure member 28 pulled downwardly which will cause the shelf 32 to swing upwardly about the axis of the hinge pin 30 thereby causing all the dice 42 to slide downwardly along the curved ramp 44 and come into engagement with the inwardly extending edge 36 of the closure member 28 wherein the dice 42 will be disposed in alignment for reading the indicia on the particular dice for playing a game.

Adjacent the top wall 14, a pair of peripheral ribs 52 is provided on the inner surface of the receptacle 12 for reinforcing the receptacle 12 and also forming projections for engagement with the dice 42 thereby assuring that the dice 42 will be thoroughly agitated during shaking of the receptacle 12 thereby eliminating the possibility of a skilled player predicting the manner in which the dice will fall.

The dice 42 are provided with picture-type indicia rather than with numbers with each side of the cube having a different picture and the different cubes may be of different colors. As example, the cube or dice 42 may have an engagement ring 54 on one side thereof, a wedding ring 56 on another side thereof and a bell designating wedding bells 58 on yet another side thereof and the five cubes 42 present 30 surfaces upon which suitable indicia may be disposed whereby a person's fortune may

be read or future events anticipated wherein a highly amusing type of game may be played entirely for entertainment purposes.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. An amusement device comprising a receptacle having an open bottom area, a top, a front wall, a rear wall and side walls with the front wall having an enlarged opening in the bottom portion thereof, a pivotal closure member for said opening with the closure member being hingedly attached to the side walls adjacent the bottom edge thereof, detent means releasably retaining said closure member in closed position, and a plurality of cubes disposed in said receptacle with each cube having indicia on each side thereof, said closure member being provided with a laterally extending platform overlying the open bottom of the receptacle when the closure member is in closed position, and a curved ramp between the platform and the closure member for directing the cubes downwardly onto the upper surface of said closure member when it swung to a horizontal position thereby raising the platform and the cubes whereby the cubes will slide down and forwardly on the ramp, and an inwardly extending free edge on the upper end of the closure member for stopping the cubes in alignment thereby permitting comparison of the indicia on the upper surface of

each cube after the cubes come to rest, the shifting weight of the cubes being sufficient to maintain the closure member in closed or open position until manually manipulated, said platform being substantially equivalent in size to the bottom area of the receptacle and having a length greater than the height of said opening for limiting the downward pivotal movement of the closure member by engaging the top edge of the opening.

2. The combination of claim 1 wherein said closure member is provided with laterally projecting tabs forming handle means for manipulating said closure member, said tabs projecting outwardly from the side edges of the closure member for engagement with the side edges of the opening for limiting the closing movement of the closure member.

3. The combination of claim 2 wherein the side edges of said ramp and portions of the closure member and platform have vertical side walls with the walls being connected to the inwardly extending free edge of the closure member for guiding the movement of said cubes, said detent means being disposed on the inner surface of the side walls of the receptacle and on the outer surface of the side walls on the platform for holding the closure member in closed position, the side walls on the ramp, closure member and platform being constant in height with a curved upper edge generally paralleling the upper surface of the closure member, ramp and platform.
